UNITED STATES PATENT OFFICE.

WILLIAM J. NESBITT, OF LOS ANGELES, CALIFORNIA.

HEEL-CUTTING APPARATUS.

1,259,432.

Specification of Letters Patent. Patented Mar. 12, 1918.

Application filed February 10, 1917. Serial No. 148,240.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to heel cutting apparatus, and it may be said to consist in the provision of the novel and advantageous features and in the novel and improved construction, arrangement, and combination of parts and devices as will be apparent from the description and claim which follow hereinafter.

20 One object of the invention is to provide a novel and improved heel cutting apparatus in which the cutter is arranged on a mounting whereby the cutter can be moved to have the cutter cut the heel, and which 25 mounting permits of the cutter being adjusted laterally toward or away from the heel, and which mounting permits of the cutter being tilted so that it will cut one side of the heel thicker than the other side, 30 and which mounting also permits of the cutter being adjusted so that it will make an angular cut longitudinally of the heel.

Another object of the invention is to provide a novel and improved heel cutting apparatus in which compressed air is utilized 35 to operate the heel holding device, and to effect movement of the cutter past the heel to cut the heel.

Other objects and the advantages of the 40 invention will be apparent to those skilled in the art from a careful consideration of the following description of the preferred construction embodying the invention, taken in connection with the accompanying drawings 45 in which—

Figure 1 is a front elevational view of the heel cutting apparatus, Fig. 2 is a side elevational view of a part of the cutter mounting, Fig. 3 is a plan view of the same; Fig. 4 is a sectional view taken on the line 4—4 of Fig. 2; Fig. 5 shows side elevational and plan views of the arm which carries the cutter; Fig. 6 is an enlarged broken side elevational view of the apparatus taken on the line 6—6 of Fig. 1; Fig. 7 is a plan view of the same; Fig. 8 is a broken sectional view

taken on the line 8—8 of Fig. 6; Fig. 9 is a broken sectional view taken on the line 9—9 of Fig. 6; Fig. 10 is a broken plan view taken on the line 10—10 of Fig. 9; Fig. 11 is an enlarged plan view of the compressed air valve; Fig. 12 is a sectional view of the valve taken on the line 12—12 of Fig. 11; Fig. 13 is a sectional view taken on the line 13—13 of Fig. 12; Fig. 14 is a plan view 65 of the frame and of a portion of the adjustable mounting for the cutter; Fig. 15 shows plan and side elevational views of the support which is adjustably mounted on the frame; and Fig. 16 shows plan and side 70 elevational views of the table which is pivotally mounted on the support.

The frame in this instance is preferably rectangular, and it consists of the front and rear upright corner angle bars 17 and 18, 75 the angle bar 19 suitably secured to the upper part of the front corner angle bars 17, the angle bar 20 suitably secured to the upper part of the rear corner angle bars 18, the side pieces 21 connected between the 80 front and the rear corner bars 17 and 18, and the brace 22 suitably connected between the front corner bars 17.

A support 23 is arranged so that it can be adjusted transversely on the frame; said 85 support 23 being provided at its ends with guide pins 24 which extend in the guideways 25 which are provided in the front and rear angle bars 19 and 20. A table 26 is connected by the pivot 27 to the upper part 90 of the adjustable support 23. The table 26 is provided with a guideway 28 into which extends the downward projection 29 on the slide 30. As shown in this instance the slide 30 is mounted between guides 31 on the top 95 of the cylinder 32 which is attached by the bolts 33 to the lugs 34 on the table 26. The circular saw or cutter 35 is mounted on the shaft 36 and is disposed between the spaced arms 37 and 38 on the forward end of the 100 shaft 39 which is pivotally mounted in the bearings 40 and 41 on the slide 30. The shaft 36 is mounted in the bearings 42 on the arms 37 and 38 and in the bearing 43 on the bracket 44 which is suitably secured to 105 the arm 38.

The support 23 may be operated by any suitable means, that shown consisting of the shaft 45 which bears pivotally in the angle bars 19 and 20 of the frame; 110 said shaft 45 having secured thereto the arms 46 to which are pivotally connected

the links 47 which are also pivotally connected to the lugs 48 on the underside of the support 23. An operating-lever 49 provided with the handle 50 is secured to the shaft 45, 5 and said lever 49 has thereon a pivot 51 on which is mounted a dog 52 adapted to engage the teeth 53 on the bracket 54 secured to one of the side pieces 21 of the frame. To the dog 52 is pivotally connected one end 10 of the link 55 which has its other end pivotally connected to the bell crank lever 56 which is pivotally connected to the lever 49 and is normally pressed away from the handle 50 by a spring 57 which is interposed 15 between the bell crank lever 56 and the handle 50.

The table 26 can be turned on the pivot 27 by means of the lever 58 to which is pivotally connected one end of the link 59 which 20 has its other end pivotally connected to the table 26. The lever 58 has a handle 60 at one end and it has its other end connected to the pivot 61 on the lateral extension 62 of the rear end of the support 23. A dog 63 25 is pivotally mounted on the lever 58 and is adapted to engage the teeth 64 on the extension 62 to lock the lever 58 in adjusted position. A link 65 has one end pivotally connected to the dog 63 and has its other 30 end pivotally connected to the bell crank lever 66 which is pivotally connected to the lever 58 and is normally pressed away from the handle 60 by a spring 67 which is interposed 35 between the bell crank lever 66 and the handle 60.

The shaft 39 can be turned on the slide 30 by means of the lever 68 which is provided with a handle 69 at one end and has its other end pivotally connected to the lateral 40 extension 70 on the slide 30; said lever 68 being connected by the link 71 to the downwardly inclined lateral extension 72 on the bracket 73 which is secured to the shaft 39. The link 71 has one end pivotally connected 45 to the lever 68 and has its other end pivotally connected to the extension 72. The lever 68 has thereon the pivoted dog 74 which is adapted to engage the teeth 75 on the extension 70 to lock the lever in adjusted position. A link 76 has one end pivotally connected to the dog 74 and has its other end pivotally connected to the bell crank lever 77 which is pivotally mounted on the lever 68 and is normally pressed away from the handle 69 by the spring 78 which is interposed 55 between the handle 69 and the bell crank lever 77.

The cutter 35 can be operated by the motor 79 which is suitably secured to the bracket 60 73 and has on its shaft 80 the sprocket pinion 81 which is connected by the sprocket chain 82 to the sprocket wheel 83 which is secured to the shaft 36.

The shoe holding device may be of any 65 suitable or approved construction; that

shown consisting of the jaws 84 and 85 which have thereon the plates 86 adapted to fit in the crease between the heel seat and the heel of the shoe 87. The jaw 84 is suitably secured to the upstanding arm 88 of a bracket 70 89 which is formed with a rearward extension 91 and is secured to the angle bar 19 by the screws 90.

As shown the heel holding device and the slide 30 which carries the cutter 35 are preferably operated by means of air under pressure. The jaw 85 is secured to the rod 92 which passes through the guideways 93 provided on the jaw 84 and is connected to the piston 94 in the cylinder 95 which is mounted on the extension 91. The piston 96 in the cylinder 32 is connected by the rod 97 to the downward extension 29 of the slide 30. A rotary valve has its casing 98 suitably mounted on the angle bar 19, and has fitted 85 in said casing 98 a rotary disk 99 provided with a stem 100 on which is removably fitted the crank 101 for operating the valve. The casing 98 is provided with the ports 102, 103, 104, 105, and 106. A pipe 107 is connected to the port 102 and leads to a tank, not shown, for supplying compressed air. A pipe 108 is connected between the port 103 and the port 109 in the upper end of the cylinder 95; a pipe 110 is connected between 95 the port 105 and the port 111 in the lower end of the cylinder 95; a pipe 112 is connected between the port 104 and the port 113 in the rear part of the cylinder 32; and a pipe 114 leads from the port 106 to the 100 port 115 in the forward part of the cylinder 32. The disk 99 is provided with the passageways 116, 117, 118 and 119, and the casing 98 is provided with the exhaust passageway 120 which is in open communication with the passageway 119, and with the passageway 118 which latter is in open communication with the passageway 117.

From the foregoing description the construction, mode of operation, and advantages 110 of the apparatus will be understood by those skilled in the art. When the shoe 87 is placed on the jaw 84 the disk 99 of the valve is turned to have the passageway 117 in communication with the port 105, and to have the passageway 116 in communication with the port 103, so that the air already in the cylinder 95 is free to pass out through the pipe 110, and the passageways 117, 118, and 120, and the piston 94 is moved down 115 by air under pressure passing through the pipe 108 to the upper part of the cylinder 95. The piston 94 moves down until the jaw 85 engages the shoe 87 so that the latter is clamped in position between the jaws 84 125 and 85. By operation of the lever 49 the support 23 and consequently the cutter 35 can be adjusted laterally toward or away from the heel of the shoe 87 according to the amount that is to be cut off of the heel. 130

- If it is desired to make an angular cut longitudinally of the heel the lever 65 can be operated to turn the table 26 on the pivot 27 and consequently turn the cutter 35 according to the angle desired. If it is desired to make an angular cut transversely of the heel to have one side thicker than the other, the lever 68 can be operated to turn the shaft 39 on the slide 30 and consequently tilt the cutter 35 according to the angle desired. After making adjustments to adjust the cutter 35 according to the cut which it is desired to make through the heel, the disk 99 can be turned until the passageway 117 is in communication with the port 106, and the passageway 116 is in communication with the port 104, so that the air already in the cylinder 32 is free to pass out by way of the pipe 114 and the passageways 117, 118, and 20 120, and the piston 96 is moved forwardly by air under pressure passing into the rear part of the cylinder 32 through the pipe 112. The forward movement of the piston 96 moves forwardly the slide 30 and effects 25 movement of the cutter 35 past the heel so that a part of the heel is cut off. If now the disk 99 is turned in a reverse direction to its first or normal position, it will be seen that the cutter 35 will be moved to its rearward position, and then the jaw 85 will be moved to its raised position out of engagement with the shoe 87.

The construction which has been particularly illustrated and described admits of changes and modifications—wherefore the right is reserved to all such changes and modifications as do not depart from the spirit and scope of the invention which is defined in the appended claim.

I claim:

Heel cutting apparatus comprising the combination of a heel holding device, a movably mounted cutter, and means for operating said heel holding device and said cutter by air under pressure, said means including a valve actuatable to effect in succession the operation of said heel holding device and said cutter, substantially as set forth.

In testimony whereof, I have signed my name to this specification at Los Angeles, county of Los Angeles, State of California, this 31st day of January, A. D. 1917.

WILLIAM J. NESBITT.
